UNITED STATES PATENT OFFICE.

JOHN E. BELL, OF BROOKLYN, NEW YORK, ASSIGNOR TO POWER SPECIALTY COMPANY, OF NEW YORK, N. Y., A CORPORATION OF NEW YORK.

STEAM-GENERATING PLANT.

Application filed July 1, 1922. Serial No. 572,166.

To all whom it may concern:

Be it known that I, JOHN E. BELL, a citizen of the United States of America, residing at Brooklyn, county of Kings, and State 5 of New York, have invented certain new and useful Improvements in Steam-Generating Plants, of which the following is a full, clear, and exact description.

The general object of my invention is to 10 provide improvements in method of, and apparatus for generating steam. More specifically the object of my invention is to provide for the more effective utilization of an economizer for transferring heat to 15 boiler feed water from the partially cooled products of combustion leaving the boiler furnace.

It has long been common practice to pre- 20 heat boiler feed water by the use of an economizer, but heretofore the economizer has ordinarily been regarded as an adjunct of the boiler, which, while of value, is distinctly of secondary importance as compared with the boiler proper. I have discovered, 25 however, that highly beneficial results, both with respect to the thermal efficiency and operating economy of a steam generating plant, and with respect to the initial construction and maintenance costs, may be 30 obtained by making the economizer a more important element of the steam generating plant than has heretofore been the case.

To this end I substantially increase the 35 ratio of economizer heating surface to boiler heating surface over that heretofore employed in commercial practice, and provide the economizer heating surface in an economizer of special construction characterized by its compactness and requiring a draft 40 much stronger than is required in the types of economizers heretofore in use to move the heating gases through it. In the preferred practical mode of carrying out my invention I employ economizer tubes similar in construction to those heretofore employed in the well known Foster superheater, in that each tube comprises an inner tube of wrought steel which is surrounded by an externally corrugated tubular cast 45 iron casing. In the economizer which I employ, the special tubes are preferably spaced closely enough together to give an aggregate external tube surface area per unit of volume of space occupied which is 50 several times greater than is obtained or is

practically possible of attainment in economizers of the types heretofore in commercial use. The compactness of the economizer which I employ not only reduces the bulk and initial cost of the economizer but 55 makes it practically feasible to enclose the economizer in a housing which forms part of the boiler setting and is sufficiently air tight to practically eliminate air leakage into the economizer, notwithstanding the 60 high draft suction impressed on the economizer.

The special economizer tube construction employed provides a very large amount of 65 external heating surface swept by the heating gases, in comparison with the internal wet surface of the tube; is well adapted for high pressure work since the steel inner tube may readily be of sufficient strength to resist an internal pressure as high or higher 70 than the boiler steam pressure, and the cast iron casing section protects the steel inner tube from the corrosive effect of the furnace gases which rapidly destroy steel 75 economizer tubes directly exposed to the 80 action of the heating gases, especially in the low temperature portion of an economizer.

Heretofore in ordinary practice, the ratio 85 of economizer heating surface to boiler heating surface has not been greater than the ratio of 7 to 10. In accordance with my present invention I make the economizer heating surface at least as great as and in some cases considerably greater than the 90 boiler heating surface. In thus increasing the ratio of economizer to boiler heating surface in a steam generating plant of given capacity, I make the amount of economizer heating surface greater and the amount of boiler heating surface smaller than has 95 heretofore been used in a steam generating plant of similar capacity and efficiency. The increase in economizer heating surface made is less however than the decrease in 100 boiler heating surface as my invention permits of a smaller aggregate boiler and economizer heating surface than has heretofore been required. The explanation of this 105 saving in total heating surface is found in the fact that the decrease in boiler and increase in economizer heating surface tends to increase the average temperature differential between the boiler heating surface and the heating gases passing through the boiler, and also between the economizer heating 110

surface and the heating gases passing through the economizer. The maximum theoretical reduction in total heating surface would be obtained by increasing the 5 ratio of economizer to boiler heating surface to the point at which the water would be heated in the economizer to the boiler steam temperature, but in practice I consider it desirable to maintain the maximum economizer water temperature below the boiler 10 steam temperature under normal conditions of operation.

The rate at which a heated gas gives up its heat to a cooler surface is, as well-known, 15 almost directly proportional to the velocity of flow of the gas over the surface, or more strictly speaking, to the product of the velocity times the gas density, or the mass flow. It is also a function of the temperature 20 of the gas and increases very materially for gas temperatures corresponding to furnace temperatures. This increase is not only due to the greater difference in temperature between the gas and the absorbing 25 surface, which is, of course, of a high order, but is also due to an increase in the transfer rate per degree difference in temperature. Heat absorbed by radiation from the furnace is roughly proportional to the 30 fourth power of the absolute temperature of the furnace. In the case of first impingement of the furnace gases and before a uniform temperature gradient has been established, I have found that the heat transmitted 35 by convection, or contact between the gases and the cooling surface is at a rate of transfer of approximately the same order as that due to radiant heat. It follows therefore, that in a boiler, still or other apparatus, 40 which absorbs heat from furnace gases, that the bulk of the heat so absorbed, which corresponds to high gas temperatures, is absorbed in such a manner as to make the velocity of the gases over the surface relatively unimportant. The same condition 45 does not, however, exist in connection with the absorption of the heat given out at the lower gas temperatures, where the velocity is the controlling factor. I, therefore, propose 50 arranging my boiler surface, which as has been pointed out, is relatively of very much smaller extent than has heretofore been used, without regard to gas velocity, and arrange the economizer surface, which is much 55 larger than heretofore used, to obtain the maximum allowable velocity compatible with the draft conditions. This necessitates 60 a comparatively small draft loss in the boiler portion, and a corresponding larger draft loss in the economizer portion to obtain the maximum temperature reduction with a given draft suction at the economizer outlet. The tubes should be horizontally 65 disposed to restrict the tendency of furnace dust to deposit on the sides of the corruga-

tion ribs and to facilitate cleaning the tubes. Furthermore, the tubes should extend transversely to the direction of flow of the heating gases and should be arranged in rows substantially transverse to the direction of flow of the heating gases, with the tubes in adjacent rows staggered; and the tubes should be closely spaced so that the average distance between tube centers is small, for example in the neighborhood of one and one 75 quarter times the maximum tube diameter, and the area of the gas path between a pair of adjacent tubes in adjacent rows transverse to the direction of the gas flow should not be less than one half the area of the gas 80 path between adjacent tubes in the same row, to insure proper contact between the heating gases and the tubes, and to minimize the frictional resistance to the flow of the heating gases through the economizer 85 and thereby minimize the draft required to move the heating gases through the bank of the economizer tubes.

Where, as will ordinarily be the case, the high draft suction required for operating a 90 steam generating plant in accordance with the present invention cannot be provided by stack or natural draft but requires an exhaust fan, I have found it advantageous to make provisions for sending a portion only 95 of the furnace gases leaving the boiler proper through the economizer when the steam generating plant is operating under peak load conditions. The diversion of a portion of the furnace gases away from the 100 economizer under peak load conditions permits of the use of an exhaust fan of smaller capacity than would otherwise be required, with a consequent decrease in initial and operating costs, and great economy in operation under normal loads. Moreover, the diversion of a portion of the furnace gases away from the 110 economizer, under peak load conditions, does not result in a corresponding decrease in the temperature to which the feed water is heated.

Where, as is frequently the case, the general direction of flow of the heating gases is upward through an economizer or economizer section, which comprises a bank of 115 horizontally disposed tubes, the temperature of the water in the tubes should increase progressively from the initial water temperature at the top of the bank to a maximum delivery temperature at the bottom of the bank. To obtain this result it is not only necessary to have the water flow back and forth through economizer tubes at successively lower levels, but it is also necessary, as I have discovered, to have a velocity of water flow through the economizer tubes which is not less than a certain critical velocity. If the velocity of the water flow is less than this critical velocity 120 practical or convection currents will be set up 125 130

- in the water in the economizer tubes which will make the temperature in the tubes at the top of the bank practically as high as the temperature in the tubes at the bottom of the bank.
- Where, in an economizer, the water flows serially through a plurality of tubes, and the conditions of operation are such as to maintain a fairly definite water temperature gradient along the path of flow, as is the case in an economizer comprising a bank of horizontally disposed tubes in which the water flows serially through tubes at successively higher levels, or flows serially at the proper velocity, as above explained, through tubes at successively lower levels, there is obtained the advantage that the corrosive effects which occur mainly at a particular water temperature are substantially restricted to the tubes normally at that temperature, and are not distributed over all or a considerable portion of the tubes in the bank. This is particularly important in connection with the corrosive action on the inner surfaces of the tubes due to air contained in the water. As is well known, water which is exposed to the atmosphere at ordinary atmospheric temperatures holds in solution a considerable amount of air and when such water is heated, the air is liberated. In the case of an economizer the oxygen in the liberated air attacks or corrodes the inner surface of the economizer tubes when the latter are made of a ferrous material such as wrought iron or steel. The water temperature at which the liberated air thus attacks the economizer tubes is believed to be 180° or thereabouts. By arranging and operating an economizer so that this critical water temperature of 180° or so, is normally maintained in the economizer tubes in one or two rows only, and making the tubes subject to this corrosive action readily removable, it follows that the destructive effect of air in the water is restricted to a comparatively few number of tubes which may be readily replaced without disturbing the large majority of uninjured tubes.
- My invention comprises methods of and apparatus for effectively utilizing the above mentioned discoveries and principles of operation. The various features of novelty which characterize my invention are pointed out with particularity in the claims annexed to and forming a part of this specification. For a better understanding of the invention, however, its advantages and specific objects obtained with it, reference should be had to the accompanying drawings and descriptive matter in which I have illustrated and described preferred embodiments of my invention.
- Of the drawings:
- Fig. 1 is a side elevation partly in section of one form of steam generating boiler and economizer arrangement;
- Fig. 2 is an elevation partly in section taken at right angles to Fig. 1;
- Fig. 3 is a partial plan on the line 3—3 of Fig. 2;
- Fig. 4 is a view taken on a larger scale than Fig. 3 showing a portion of the damper arrangement of Fig. 3;
- Fig. 5 is a section on the line 5—5 of Fig. 3;
- Fig. 6 is a partial section on the line 6—6 of Fig. 1; and
- Fig. 7 is an elevation partly broken away and in section of a modified form of economizer arrangement.
- In the drawings, and referring first to the construction shown in Figs. 1 to 6, A represents a boiler furnace of conventional type, with a water tube boiler B, above the furnace combustion chamber A'. The boiler B as conventionally illustrated, comprises front and rear headers B' and B² connected by inclined water tubes B³, and a steam and water drum B⁴ to which the rear headers B⁵ are connected by conduits B⁶, and to which the front headers B' are connected by horizontal tubes B⁷. Baffles B⁸ and B⁹ cause the furnace gases to travel across the water tubes in a plurality of passes from the combustion chamber A' to the furnace gas outlet A². C are superheater tubes located in the space between the tubes B³ and B⁶ and between the first and second passes for the furnace gases.
- Mounted above the boiler furnace proper is the economizer D which, in the construction illustrated, comprises two vertically elongated banks of horizontally disposed economizer tubes D'. The tubes D' are enclosed in a housing which, in the preferred construction illustrated, comprises an inner metallic shell D² and an outer metallic shell D³ with a space D⁴ between the two shells which is filled with a suitable material such as powdered Sil-o-cel which serves both as a heat insulating material, and also as a packing preventing leakage through the joints in the shells D² and D³. The tubes D' each comprise an inner tube d of wrought steel and an externally corrugated tubular casing d' formed of cast iron sections which fit snugly on, and may be shrunk in place on the tubes d. Various provisions may be made for supporting and connecting the different tubes D'. In the simple and effective construction illustrated, the tubes D' are supported in the end walls of the shell D² and in an apertured tube sheet D⁵ placed midway between the end walls. One of the end walls is formed with apertures D⁶ a trifle larger than the maximum diameter of the tubes D', so that the latter may be axially removed from, and replaced in the housing through these apertures when con-

ditions make this desirable. The tube sheet D^5 is formed with tube receiving apertures D^7 similar to the apertures D^6 . The apertures D^8 formed in the opposite end wall of the economizer housing are only large enough to receive the bare ends of the inner tube portion d of the tubes D' . The tubular casings d' of the tubes D abut against the inner side of the end wall of the portion of the shell D^2 in which the holes D^8 are formed, and at the opposite end of the economizer, the ends of the casings d' may well be substantially flush with the outer surface of the portion of the shell D^2 in which the holes D^6 are formed.

In the construction illustrated the tubes D' in the top row of each economizer bank, each has one end expanded or otherwise secured in a supply header D^9 . Similarly the bottom row tubes D' each have one end expanded or otherwise connected to the outlet header D^{10} of the economizer. In the particular construction shown, each of the economizer tubes in each intermediate row of the economizer is connected at one end by a return bend D^{11} to the corresponding end of the tube D' in the row immediately above, and has its opposite end connected by a return bend D^{11} to an economizer tube in the subjacent row. As shown in Fig. 1 the economizer tubes in adjacent rows are staggered, and the side walls of the shell D^2 are advantageously corrugated as shown in Fig. 1 in conformity to the staggered arrangement of the tubes D' so as to restrict the flow of the heating gases through the spaces between the side walls and the adjacent tubes D' .

The two banks of economizer tubes are separated by a passage D^{12} which advantageously is formed with metal side walls D^{13} corrugated to conform to the staggered arrangement of the tubes D' . The passage D^{11} forms a by-pass through which a portion of the heating gases may be passed under peak load conditions. Flow through the by-pass passage D^{12} may be controlled by a damper or dampers of any usual or suitable form. Preferably, however, the special damper arrangement comprises a plurality of horizontally extending dampers E arranged one above the other in the passage D^{12} . Each of these dampers may be rotated from a vertical wide open position, into a horizontal closed position. In some cases each damper E may extend the full horizontal depth of the channel D^{12} , but in the construction shown, this channel is subdivided into four flues by the tube sheet D^6 and intermediate division walls D^{14} , and four dampers E , one for each flue, are provided at each damper level in the economizer. Each damper E may advantageously be formed, as shown best in Figs. 3, 4 and 5, of spaced apart sheet metal plates

E' connected together, and each damper is provided at its ends with a suitable pintle or spindle extension E^2 which is journaled in the corresponding division or end wall of the channel D^{12} . As shown, the two aligned dampers at each side of the central division wall D^6 are connected by a common pintle or spindle part E^2 , and each damper adjacent the end wall of the channel D^{12} has its corresponding pintle E^2 projecting through the end wall and provided with an external operating connection. The operating connections for the dampers E shown, comprise a gear segment E^3 connected to the outer end of each externally projecting pintle E^2 , and an operating shaft E^4 at each end of the economizer provided with worm sections E^5 in mesh with the corresponding gear segments E^2 . As shown each shaft is provided with a hand wheel E^6 by which it may be rotated to open and close the corresponding dampers. In its closed position each damper section extends into close proximity to the adjacent portions of the by-pass side walls D^{13} (see Fig. 5) but need not make a perfectly tight joint with the latter since, in accordance with the principle involved in the ordinary labyrinth packing, the series of dampers E in each flue portion of the by-pass serve, when closed, to prevent any appreciable flow through that flue portion, even though the joints at the edges of any one damper E in the series are open enough to permit an appreciable flow through those joints if subjected to the pressure differential at the opposite ends of the flue.

The fact that in the by-pass damper arrangement described no one of the series of dampers E provided need actually seal the by-pass greatly simplifies the construction and operation of the dampers, especially since with this construction, contraction and expansion or distortion of the parts resulting from the varying temperatures to which they are subjected do not interfere with the operation or effectiveness of the dampers. To permit the removal and replacement of the dampers the central division wall D^6 , the intermediate division walls D^{14} and the portions of the shell D^2 at the ends of the by-pass channel D^{12} are formed with slots D^{15} large enough to permit the passage therethrough of the dampers when the latter are vertically disposed and are raised upward from their normal positions in which the pintles E^2 rest against the bottom edges of these slots. Removable covers D^{16} may be provided for the slots D^{15} in the shells D^2 and D^6 , but the slots D^{15} in the division wall D^6 and intermediate walls D^{14} need not be closed.

The connection F between the economizer housing proper and the boiler housing for passing the furnace gases to the economizer from the boiler housing outlet A^2 is advan-

tageously formed, similarly to the economizer housing, with inner and outer metallic shells and insulating material between the shells.

5 Above the economizer is located an exhaust fan G for creating the draft suction required to move the furnace gases through the boiler and economizer at the desired velocity. The connection H between the exhaust fan casing proper, and the economizer housing is advantageously formed of metal which need not be insulated as heat radiation from the shell is desirable since it reduces the temperature and volume of the 15 gases passing from the economizer and the heat thus lost would not be utilized in the apparatus in any event.

The feed water is supplied to the economizer by a supply pipe I ordinarily connected to the outlet of a boiler feed pump (not shown). The pipe I is connected to the top economizer header D⁹, and the boiler feed water is forced through the economizer tubes and into the boiler against the pressure of 25 the latter through the conduit J connecting the bottom economizer header D¹⁰ to the steam and water drum B⁴. In many cases I prefer to employ a boiler feed controller automatically regulating the flow of feed water into the boiler in response to the requirements, and this 30 may operate in a known manner either to directly control the delivery of water to the economizer, or to directly control the flow of water from the economizer into the boiler. In any event the pressure of the water in the 35 economizer tubes must be as high as, and in some cases may be appreciably above the pressure in the steam and water drum B⁴ of the boiler, which will ordinarily be 250 pounds or above, in steam generating plants constructed in accordance with the present invention.

With the special form of economizer tube shown, the internal steel tube d provides the strength to resist the internal pressure to which it is subjected, while the cast iron casing d' is to a large extent immune to attack by the furnace gases, and such pitting or other injury as it may receive in time from the corrosive effect of the furnace gases does not weaken the resistance of the tubes to the internal bursting pressure to which 50 they are subjected, and does not appreciably effect the heat absorbing capacity of the cast iron casing. This heat absorbing capacity is of course greatly enhanced by the relatively great amount of external heating surface in contact with the furnace gases which it provides. The area of external gas swept heating surface of each tube may advantageously be in the neighborhood of 5 1/2 to 6 1/2 times as great as in the internal wet surface area of the tube.

65 In the construction shown in Figs. 1 and

2 the externally corrugated economizer tubes D' are arranged in horizontal rows which extend transversely to the general direction of gas flow past them, and are also arranged in rows extending parallel to the 70 general direction of gas flow, the tubes in the adjacent horizontal or transverse rows being staggered. The tubes D' are closely spaced. In ordinary practice I prefer to make the average of the distances between 75 the centers of each tube D' and the centers of the immediately adjacent tubes about one and one quarter times the maximum tube diameter. Notwithstanding the small space between the exterior surfaces of the 80 economizer tubes, the internal tubular parts d are sufficiently far apart to permit the ready use of suitable end connections between the different tubes, since these connections are external to the inner metal 85 shell D² of the economizer housing, and the tube casings d' need not project through the shell D². With this spacing the external heat absorbing surface if the economizer per 90 unit of space occupied by the bank of economizer tubes is several times greater than is practically possible with economizer tubes of the same internal diameter and having smooth external walls, especially since with the smooth walled tubes the minimum distance between the tubes is limited by the necessity for providing space for the necessary end connections to the tubes.

Suitable provisions should be made for 95 blowing or washing dust off of the economizer tubes at sufficiently frequent intervals. In the preferred construction illustrated, the provisions for this purpose comprise water spray pipes K horizontally disposed above the banks of economizer tubes and extending 100 transversely to the tubes, and suitable connections for supplying water at intervals to these spray pipes. Advantageously the water supply connections are arranged so 105 that water is discharged from only a few of the pipes K at a time, to thereby avoid undue cooling of any one economizer tube as a whole, and to avoid the disturbance in draft conditions which would be created by the very considerable volume of steam which 110 would be generated if water were simultaneously discharged from all of the spray pipes K. Suitable pockets D²⁵ may advantageously be provided, as shown, at the bottom of the economizer housing to receive the 115 clean-off water and dust with valved drain pipe connections D²⁶ discharging from the pockets.

In the contemplated construction and mode of use of the apparatus shown in Figs. 125 1 to 6, the aggregate heating surface of the economizer swept by the heating gases is at least as great as the aggregate heating surface of the boiler proper so that a much larger portion of the total amount of heat 130

6
abstracted from the heating gases is absorbed by the economizer than has been the practice heretofore where the economizer heating surface has ordinarily been 70% or 5 less of the boiler heating surface. The distribution of boiler and economizer heating surface which I employ makes it possible to obtain a relatively high amount of superheat with a superheater of moderate size located 10 above the main bank of water tubes.

The close spacing of the economizer tubes, and their corrugated exterior surfaces provide tortuous gas paths through which the heating gases move with relatively high velocity thus insuring a high heat transmission factor and a large economizer capacity per unit of volume. The consequent comparatively small economizer volume required for a given duty makes it practically feasible to 20 employ an economizer housing which is substantially air tight, thus practically eliminating air leakage into the economizer notwithstanding the comparatively high draft suction required to move the heating gases 25 through the boiler and economizer. Air leakage is objectionable both because of the cooling effect of the air leaking in, and also because of the resultant increase in volume of the gases which must be handled by the 30 draft creating fan. Air leakage tending to increase the exhaust fan capacity required is especially objectionable in the practice of my invention because the relative high draft suction which I ordinarily employ requires 35 a considerable expenditure of fan driving energy at normal load even when there is no leakage at all. It has heretofore been the practice to operate a boiler plant comprising an economizer with a draft suction 40 which ordinarily does not exceed one and three quarter inches of water, at a maximum. In proceeding in accordance with the present invention I may advantageously employ 45 a draft suction at normal load as high as three, four, or five inches of water, and of which much more than half is utilized in moving the heating gases through the economizer.

The relatively high draft suction at normal 50 load which I prefer to employ, makes the economizer by-pass D^{12} of especial importance, as becomes apparent when account is taken of the great increase in exhaust fan capacity and driving power which would be required if all the heating gases were drawn 55 through the economizer under the peak load conditions which may prevail for an hour or so out of each twenty-four hours of service. Assume, for example, a plant in which the 60 boiler heating surface proper is ten thousand square feet, and the normal load involves the operation of 400% of rating, while for an hour or so out of each twenty-four hours, the boiler must be operated at 640% of rating; and also assume that when operating

at normal load, the draft suction at the fan inlet is three inches, and 20 H. P. is required to operate the fan. On the further assumption that the fan inlet temperatures are the same at peak load as at normal load, the volume of heating gases to be handled by the fan under peak load conditions, will be eight-fifths of that handled at normal load. To move this increased volume of gases through the boiler and economizer the fan inlet suction must be increased from three inches to 75

$$\left(\frac{8}{5}\right)^2$$

times three inches or about seven and two-thirds inches. The fan driving force required for operating the fan at the increased load will be increased in proportion to the product of the volume of gas handled and the suction required to move the gas; in other words, the driving force required for the fan under peak load conditions will be, not 20 H. P., but

$$\left(\frac{8}{5} \times \frac{8}{5}\right)^2$$

times 20 H. P., or about 82 H. P. Actually the temperature of the gas at the fan inlet will be higher under peak load conditions than under normal load conditions, and this involves some further increase in the power required to operate the fan. If, instead of passing all the heating gases through the intertube space of the economizer under the peak load conditions assumed, a third of the heating gases are then drawn through the by-pass D^{12} , the volume of gas drawn through the economizer under the peak load conditions will be sixteen-fifteenths (i. e.

$$\left(\frac{8}{5} \times \frac{2}{3}\right)^2$$

of the volume of gas at normal load; the draft suction necessary to move this gas through the economizer will be about one and one-eight (i. e.

$$\left(\frac{16}{15}\right)^2$$

times the suction required to move the gas through the economizer at normal load; and the fan driving force required to move the gas through the economizer will be a little over 24 H. P. (i. e.

$$\left(\frac{16}{15}\right)^3 \times 20 \text{ H. P.}$$

Furthermore, on account of the higher temperature of the gases entering the economizer under peak load conditions, and the greater velocity of gas flow through the economizer, the portion of the heating gas flowing through the economizer at peak load with the by-pass D^{12} open will heat the

boiler feed water in the economizer up to, or nearly to the temperature to which it is heated in normal operation.

The effective utilization of my compact 5 economizer requires a progressive graduation in temperature of the water flowing through the economizer from the water inlet temperature at the top of the economizer, to the delivery temperature at the bottom 10 of the economizer. I have found that this result can be obtained in an economizer in which the general direction of flow of water through a bank of horizontally disposed tubes is downward, only when the velocity 15 of water flow through the economizer tubes is equal to, or above a certain critical velocity.

If the velocity of water flow through the economizer tubes is less than this critical 20 velocity, there is a tendency to the maintenance of parasitical or convection currents in the water in the tubes substantially equalizing the water temperature throughout the economizer tube system, so that the 25 temperature in the upper economizer tubes will be practically as high as the temperature in the lower tubes of the economizer. The exact critical velocity which must be 30 equaled or exceeded to insure the desired temperature graduation from top to bottom of an economizer in which the water flow is downward depends upon a number of factors, some of which are 35 difficult to predetermine with precision. The critical velocity may be readily determined experimentally however in the case of any particular economizer and set of operating conditions, and by way 40 of example I will state that in the case of a steam generating plant such as that shown in Figs. 1 and 2, operating at 250% of rating, and with a boiler pressure of 250 pounds and with the economizer tubes of 45 two inches internal diameter, the critical velocity of water flow through the tubes of the economizer is in the neighborhood of one half foot per second. For the practical utilization of this feature of my invention 50 I connect the tubes of the economizer so that the normal rate of flow through the economizer tubes at the lowest rate of evaporation 55 at which it is contemplated to operate the boiler for any considerable portion of the time will be at least as high as the critical velocity. It is apparent, of course, 60 that the velocity of flow through the economizer tubes depends on the number of separate paths of flow provided between the economizer inlet and outlet. Thus in the 65 economizer in which there are fourteen economizer tubes in each horizontal row, if the economizer tubes are connected (as shown in Figs. 1 and 2) so that each tube in one row is separately connected to a tube in the adjacent row there will be fourteen

paths of flow between the economizer inlet and economizer outlet. If the tubes in each horizontal row were connected in pairs so that the water entering one end of a tube would pass through that tube to the opposite end of the economizer, and would then return through another tube in the same row before passing to a tube in a lower row, there would be but seven paths of water flow through the economizer, and the velocity of flow for a given quantity of water flowing would be twice as great as in the instance first given. As already explained, the effect of maintaining a definite graduation of water temperature in the economizer 70 tubes is to confine the internal corrosive action of liberated air to the comparatively few tubes in which the normal temperature is that at which the corrosive action mainly occurs. Thus, if in the economizer shown in 75 Fig. 1, the temperature in the tubes at the level indicated by the line X, is normally about 180°, the corrosive action of liberated air will be mainly confined to the tubes at that level. With the described method 80 of mounting and connecting the tubes, it will be apparent to those skilled in the art that any particular tube or tubes may be readily replaced. With the particular form 85 of end connections illustrated, the replacement of the tube elements involves cutting off the ends of the inner tubes d of the corresponding elements which are readily accessible for this purpose, after which the 90 elements are axially removed through the 95 openings D⁶ and D⁷ in the tube supporting openings D² and D⁵, respectively. It will be understood, of course, that the metallic outer 100 wall D³ is formed with removable sections to permit tube replacements, but the particular provisions made for this purpose 105 form no part of my present invention and hence are not illustrated herein.

In Fig. 7, I have shown a modified form of economizer in which the economizer tubes D' are arranged in two banks D²⁸ and D²⁹ separated by a partition D³⁰ and arranged in an economizer housing provided with an inlet D³¹ for heating gases opening to the under side of the tube bank D²⁸ and with a chamber D³² through which the heating gases pass 110 from the top of the bank D²⁸ into the top of the bank D²⁹, and with an outlet D³³ for the spent heating gases opening from beneath the tube bank D²⁹. The external walls 115 of the housing of the economizer DA may be similar in construction to the housing walls of the economizer D. In the economizer DA the water to be heated passes initially through the header D³⁴ into the tubes D' in the lower row of the tube bank D²⁹. Thence the water passes upward through the tubes 120 in the bank D²⁹ to a top header D³⁵ to which the various tubes in the top rows of both tube banks D²⁸ and D²⁹ are connected. From 125 130

the header D^{35} the water passes downward through the tubes in the bank D^{28} to the header D^{36} to which the tubes in the lower row of the bank D^{28} are connected. From 5 the header D^{36} the water may pass to the boiler through suitable connections not shown.

In each of the tube banks D^{28} and D^{29} of the economizer DA the general direction of 10 water flow is counter to the flow of the heating gases through the intertube space of the tube bank. To obtain the full advantage of this counter flow, the velocity of water flow through the tubes in the bank D^{28} must 15 be equal to or exceed the critical velocity previously mentioned. In so far as the bank D^{29} is concerned, however, the desired water temperature graduation from bottom to top of the bank will be obtained regardless of 20 the velocity of flow through the individual tubes of the tube bank, and the tubes D' of the bank D^{29} may be so connected as to give a flow velocity through them which is less than the critical velocity if condition makes 25 this desirable.

In the economizer DA, ports D^{37} are formed in the portion of the wall D^{30} beneath the two banks D^{28} and D^{29} . Dampers EA are provided to regulate the flow of 30 heating gases through the ports D^{37} which thus provide a by-pass about both banks of economizer tubes between the inlet D^{31} and outlet D^{32} through which a portion of the 35 heating gases may be passed under peak load conditions. To avoid all possibility of undesirable steam and air accumulations in the top economizer headers, and to guard against excess pressure in the economizers, the top header D^o of the economizer D, and 40 the top header D^{35} of the economizer DA may each be provided with one or more pressure relief or safety valves L.

Certain novel features of construction and arrangement disclosed but not claimed herein are claimed in my co-pending application, Serial No. 336,284, filed November 7, 1919, of which this application is, in part, a continuation.

While in accordance with the provisions 45 of the statutes, I have illustrated and described the best forms of carrying out my invention now known to me, it will be apparent to those skilled in the art that changes in the form of the apparatus and modes 50 of operation described herein may be made without departing from the spirit of my invention as set forth in the appended claims, and that certain features of my invention 55 may sometimes be used to advantage without a corresponding use of other features.

Having now described my invention, what I claim as new and desire to secure by Letters Patent, is:

1. In a steam generating plant comprising 60 a boiler furnace and a boiler section having

storage capacity for a variable amount of water, and having a steam and water space, the improvement which consists in an economizer section traversed by the boiler furnace heating gases after the latter have left 70 the boiler section and through which water is passed into the boiler section, and formed of staggered rows of steel tubes encased in externally corrugated tubular cast iron sections, said tubes being so proportioned as to 75 provide an aggregate economizer heating surface approximately as great as the aggregate boiler heating surface, and so spaced as to require a draft suction at normal load to move the heating gases through the economizer section at least as great as the draft suction required to move the heating gases through the boiler section.

2. The combination with a boiler and its furnace, of an economizer comprising a bank 80 of horizontally disposed tubes externally swept by the heating gases leaving the furnace and through which feed water is passed into the boiler, said tubes being each provided with external circumferentially extending ribs proportioned and disposed to 85 make the external surface area of the tube several times greater than its internal surface area, and being each of a length many times greater than its maximum diameter, 90 and being spaced to provide an external tube surface area per unit of space occupied by said bank which is several times greater than is practically possible with tubes which are 95 of the same internal diameter and have 100 smooth outer walls.

3. The combination of claim 2 further characterized by the fact that each of the economizer tubes comprises an inner thin walled steel tube, and a cast iron casing 105 therefor of tubular form and externally corrugated.

4. In apparatus of the kind described, the combination with a bank of tubes having external circumferentially extending heat absorbing ribs on their body portions and having bare ends, a gas passage traversed by said tubes and having opposed metallic walls in which the ends of the tubes are supported and from the outer sides of which the bare 110 ends of the tubes project, one of the walls having tube openings of a size to permit the longitudinal passage of the ribbed portions of the tubes, return connections to which the bare ends of the tubes are secured, and heat 115 insulating material in which the portions of said tubes projecting through said walls and said return connections are embedded, and which engages the outer sides of said walls 120 and minimizes gas leakage through the latter. 125

5. The method of operating an economizer comprising a bank of horizontally disposed tubes connected to provide paths of water flow between the tubes at the top of the bank and the tubes at the bottom of the bank 130

passing successively through intermediate tubes at different levels, which consists in passing heating gases upward through the inter-tube space of the bank, and passing 5 the water along said paths of flow from the top to the bottom of the bank with a velocity of water flow through the tubes in excess of that permitting equalization of temperature in tubes at different levels by convection currents of the water in the tubes.

6. The combination with a boiler furnace, of means providing an outlet passage for the heating gases issuing from said furnace, a bank of economizer tubes traversing a portion 15 of said passage and a conduit having imperforate walls connected at its ends to said gas passage to form a by-pass about the portion of the latter traversed by the economizer tubes, and a series of dampers distributed along the length of said conduit and each adjustable from an open position into a 20 closed position in which it substantially closes but does not entirely seal the conduit.

7. An economizer comprising a casing provided with an inlet and an outlet for heating gases, and to banks of economizer tubes located therein and providing parallel paths of flow for the heating gases between the inlet and outlet and spaced apart from one another to provide between them a by-pass between said inlet and outlet, and means regulating the flow through said by-pass.

8. The combination of claim 2 further characterized by the arrangement of the tubes in rows transverse to the direction of flow of the heating gases with the tubes in each such row staggered with respect to the tubes in each adjacent row, and with the tubes in the different rows so spaced that the area of the gas path between any two adjacent tubes in adjacent rows is not less than half of the area of the gas path between two adjacent tubes in the same transverse row.

In testimony whereof I hereto affix my signature.

JOHN E. BELL.
